US00D999778S

(12) **United States Design Patent** (10) **Patent No.:** **US D999,778 S**
Tosi et al. (45) **Date of Patent:** **** Sep. 26, 2023**

(54) **DISPLAY WITH GRAPHICAL USER INTERFACE FOR SURFACING ACTION ITEMS**

(71) Applicant: **HEWLETT PACKARD ENTERPRISE DEVELOPMENT LP**, Houston, TX (US)

(72) Inventors: **Thomas Tosi**, Nashua, NH (US); **Heidi Tosi**, Nashua, NH (US); **Janice Mary Foley**, Roseville, CA (US)

(73) Assignee: **Hewlett Packard Enterprise Development LP**, Spring, TX (US)

(**) Term: **15 Years**

(21) Appl. No.: **29/803,423**

(22) Filed: **Aug. 12, 2021**

(51) LOC (14) Cl. **14-04**

(52) U.S. Cl.

USPC **D14/485**

(57) **CLAIM**

The ornamental design for a display with graphical user interface for surfacing action items, as shown and described.

DESCRIPTION

The sole FIGURE is a front view of a display with graphical user interface for surfacing action items.

The outermost broken line rectangle shows a display and forms no part of the claimed design. The remaining broken lines illustrate portions of the graphical user interface that form no part of the claimed design.

1 Claim, 1 Drawing Sheet

The screenshot displays the Global Navigation interface with the following components:

- Header:** Global Navigation
- Left Sidebar:** Support Center
- Top Bar:** Welcome, Cases Awaiting Your Action (3), Open Cases (47), Awaiting Action (0), In Progress (0), & Critical (0), View by Country (United States), and Log Out.
- Case Status Indicators:** Two circular diagrams representing case status. The top diagram has a central triangle icon and four surrounding circles, with the text "In Progress" above it. The bottom diagram has a central triangle icon and four surrounding circles, with the text "Awaiting Action" above it.
- Case List:** A table showing the following data:

Case ID	Status	Actions
CASE 123456789	Complete Action Plan	→
CASE 987654321	Complete Action Plan	→
CASE 654987123	Complete Action Plan	→
- Other Metrics:** Security Alerts (0), Critical Downloads (0), and Expiring Contracts (0).
